TRI-SULFA ALUMINUM SALTS

Carl J. Lintner, Jr., Kalamazoo Township, Kalamazoo County, Mich., assignor to The Upjohn Company, Kalamazoo, Mich., a corporation of Michigan

No Drawing. Application February 1, 1956,
Serial No. 562,650

7 Claims. (Cl. 260—239.65)

This invention relates to novel aluminum salts of sulfonamides. More particularly, this invention relates to aluminum salts of certain sulfonamides which possess an unpleasant taste. This application is a continuation-in-part of Serial 331,310, filed January 14, 1953, now abandoned.

Among the valuable sulfonamide drugs are sulfacetamide (N^1 -acetylsulfanilamide), sulfamethazine (4,6-dimethyl-2-sulfanilamidopyrimidine), sulfisoxazole [N^1 -(3,4-dimethyl-5-isoxazolyl) sulfanilamide], sulfadimetine (2,6-dimethyl-4-sulfanilamidopyrimidine), and sulfathiazole (N^1 -2-thiazolylsulfanilamide). These and other sulfonamides are generally useful as antibacterial agents. More particular types of utility may be illustrated by that possessed by sulfacetamide and sulfamethazine. Sulfacetamide is advocated for the treatment of urinary tract infections. It is active against *Staphylococcus aureus*, *Streptococcus fecalis*, *Escherichia coli*, *Aerobacter aerogenes* and *Proteus ammoniae*. Gonorrhea has responded clinically. At least one investigator concluded that it was preferable to other sulfonamides as a urinary antiseptic on the basis of pharmacological properties and toxic effects. It has been used effectively and safely for children and during pregnancy. Another investigator used it for meningococcus meningitis. Sulfamethazine is useful for hemolytic streptococcal, pneumococcal, meningococcal, staphylococcal and certain urinary tract infections.

In addition to the foregoing individual uses, these sulfonamides in the form of the novel compounds of the present invention, are advantageously used in combination with antibiotics, such as penicillin, neomycin, streptomycin, erythromycin, bacitracin, circulin, aureomycin, chloromycetin, terramycin combinations of the foregoing, or the like. The novel compounds of the present invention are also useful in compositions with the following: analgesics and antipyretics, such as aspirin, phenacetin, salicylamide, acetylparaaminophenol, or the like; bronchodilators, such as ephedrine, methoxyphenamine hydrochloride, or the like; antihistamines, such as diphenhydramine hydrochloride, prophenpyridamine maleate, pyrilamine maleate, tripeptenamine citrate, or the like; antispasmodics, such as methantheline bromide, scopolamine methyl bromide, or the like; sedatives, such as barbiturates, carbromal, or the like; diuretics, such as sodium mercurophylline, aminophylline, or the like; urinary antiseptics, such as methenamine, methenamine mandelate, or the like; and other adjuvants or synergists.

In view of these important uses and the ease of administration which accrues to the manufacture of oral preparations, the preparation of palatable tablets or liquid preparations containing one or more of the above-named objectionable tasting sulfonamides has been a serious problem to the pharmaceutical industry. Their obnoxious taste, generally characterized as bitter or astringent with a lingering after-taste, has been difficult to disguise.

It is therefore an object of this invention to provide novel salts of bad tasting sulfonamides, such as sul-

2

famethazine, sulfacetamide, sulfisoxazole, sulfadimetine, and sulfathiazole, which salts are particularly well-suited for oral administration because of their tastelessness.

It is also an object of this invention to provide novel aluminum salts of bad tasting sulfonamides, such as sulfamethazine, sulfacetamide, sulfisoxazole, sulfadimetine, and sulfathiazole, which salts can be efficiently absorbed from the alimentary tract.

Another object is to provide novel aluminum salts of bad-tasting sulfonamides such as sulfamethazine, sulfacetamide, sulfisoxazole, sulfadimetine, and sulfathiazole which salts, because of more gradual absorption from the alimentary tract, result in more prolonged sulfonamide blood levels and greater therapeutic effectiveness.

Still another object is to provide novel aluminum salts of unpleasant-tasting sulfonamides, such as, sulfamethazine, sulfacetamide, sulfisoxazole, sulfadimetine, and sulfathiazole, which salts, also because of more gradual absorption from the alimentary tract, result in fewer undesirable side reactions such as nausea and vomiting. Other objects will be apparent to one skilled in the art to which the invention pertains.

The foregoing and additional objects have been accomplished by the provision of aluminum trisulfonamide salts which have the following formula:

wherein R_1 is a radical selected from the group consisting of sulfacetamide, sulfamethazine, sulfisoxazole, sulfadimetine, and sulfathiazole, and R_2 and R_3 are radicals selected from the group consisting of sulfamethazine, sulfacetamide, sulfisoxazole, sulfamerazine, sulfadiazine, sulfapyridine, sulfathiazole, sulfaguanidine, and sulfadimetine.

In general, these sparingly soluble aluminum trisulfonamide salts are prepared by mixing together aqueous solutions containing the desired number of equivalents of soluble salts of bad-tasting para-aminobenzenesulfonamides including at least one equivalent of a water-soluble salt of a member selected from the group consisting of sulfamethazine, sulfacetamide, sulfisoxazole, sulfadimetine, and sulfathiazole, such as the sodium or potassium salt thereof, with a water-soluble aluminum salt, such as aluminum sulfate, aluminum chloride, or alum. The precipitate of aluminum trisulfonamide is collected by filtration, washed with water and dried. The reaction is operative at any temperature between about zero degrees centigrade and about 100 degrees centigrade, although temperatures between about zero degrees centigrade and room temperature are preferred. Although water is the preferred solvent for this reaction, any solvent predominantly aqueous such as one consisting of a major portion of water and a minor portion of water-miscible lower alcohols or glycols is operative.

In one embodiment of the invention, a mixture of two or more different sulfonamides, including at least one bad-tasting sulfonamide such as sulfamethazine, sulfacetamide, sulfisoxazole, sulfadimetine, or sulfathiazole, can be used in the reaction to obtain an aluminum sulfonamide complex in which, for example, one atom of aluminum is bound to one molecule of sulfamethazine, one molecule of sulfacetamide and one molecule of sulfadiazine; or, for example, one atom of aluminum is bound to two molecules of sulfamethazine and one molecule of sulfacetamide; or, for example, one atom of aluminum is bound to three molecules of three different sulfonamides, including at least one bad-tasting sulfonamide such as sulfamethazine, sulfacetamide, sulfisoxazole, sulfadimetine, or sulfathiazole.

Experiment shows that any sulfonamide radical is capable of combining with aluminum to form a water-insoluble salt. The present invention encompasses aluminum trisulfonamide salts of the following formula:

wherein R_1 is a radical selected from the group consisting of sulfacetamide, sulfamethazine, sulfisoxazole, sulfadimine, and sulfathiazole, and R_2 and R_3 are radicals selected from the group consisting of sulfamethazine, sulfacetamide, sulfisoxazole, sulfamerazine, sulfadiazine, sulfapyridine, sulfathiazole, sulfaguanidine, and sulfadimine.

The present invention also encompasses aluminum trisulfonamide salts in which the three valences of the aluminum are satisfied by the same member of the group consisting of sulfacetamide, sulfamethazine, sulfisoxazole, sulfadimine, and sulfathiazole; for example, aluminum trisulfacetamide, aluminum trisulfamethazine, aluminum trisulfisoxazole, aluminum trisulfadimine, and aluminum trisulfathiazole.

The term "sulfonamide," as used herein, includes sulfanilamide and the various sulfanilamide derivatives obtained by replacing one of the hydrogen atoms on the amido nitrogen or N^1 atom by another group. Dibasic acid substituents on either nitrogen of the sulfanilamide are inoperative for the purpose of the present invention since they may lead to the interaction of one sulfonamide with two atoms of aluminum, or with two valences of one atom of aluminum. The sulfonamides of the invention preferably have an unsubstituted amino group, i. e. two hydrogen atoms on the N^4 atom. Examples of the preferred sulfonamides of this invention include sulfamethazine, sulfacetamide, sulfisoxazole, sulfamerazine, sulfadiazine, sulfapyridine, sulfathiazole, sulfaguanidine, sulfadimine, and the like.

The following examples are illustrative of the process and products of this invention and are not to be construed as limiting.

Example 1.—Aluminum trisulfamethazine

where Z stands for a sulfamethazine radical having the following structural formula:

Two grams (0.0067 mole) of sodium sulfamethazine was dissolved in three milliliters of water and 0.666 gram (0.001 mole) of hydrous aluminum sulfate,

was dissolved in two milliliters of water. The aluminum sulfate solution was added with constant stirring to the sodium sulfamethazine solution at room temperature. A precipitate of aluminum trisulfamethazine formed immediately, was recovered by filtration using reduced pressure and subsequently washed twice with one-milliliter portions of water. After the precipitate had been removed from the filter funnel and placed in a small evaporating dish, the precipitate was dried in a hot air oven at forty degrees centigrade.

The dried aluminum trisulfamethazine was white in color. No melting point could be determined. It was tasteless. The product, which is amorphous when observed under a polarizing microscope, weighed 1.70 grams (99 percent of theory). The official assay method

for sulfonamides of the United States Pharmacopeia (sodium nitrate method) indicated 87.1 percent sulfamethazine.

Example 2.—Aluminum trisulfacetamide

wherein Y stands for a sulfacetamide radical having the following structural formula:

NaY was formed as follows:

Analytical grade sodium hydroxide (10.56 grams; 0.264 mole) was dissolved in 75 milliliters of water and to this solution 56.56 grams (0.264 mole) of sulfacetamide was added. The mixture was shaken until sodium sulfacetamide had formed as evidenced by formation of a clear solution. Hydrous aluminum sulfate,

(26.65 grams; 0.040 mole), was dissolved in 35 milliliters of water and the aluminum sulfate solution was then added rapidly with rapid stirring to the sodium sulfacetamide solution. A white precipitate of aluminum trisulfacetamide was formed. The precipitate was collected on a fritted glass filter, washed twice with successive ten-milliliter portions of distilled water, and finally dried in a hot air oven at forty degrees centigrade.

The dried aluminum trisulfacetamide was white in color. No melting point could be determined. It was completely tasteless. The official assay method for sulfonamides of the United States Pharmacopeia (sodium nitrate method) indicated 78.84 percent sulfacetamide.

Example 3.—Aluminum monosulfamethazine monosulfacetamide monosulfadiazine

wherein Z is the sulfamethazine radical, Y is the sulfacetamide radical and X is the sulfadiazine radical.

Sodium sulfamethazine (33.03 grams; 0.11 mole), sodium sulfacetamide (25.98 grams; 0.11 mole) and sodium sulfadiazine (29.95 grams; 0.11 mole) were dissolved in ninety milliliters of water. Hydrous aluminum sulfate, $Al_2(SO_4)_3 \cdot 18H_2O$ (33.32 grams; 0.05 mole), was dissolved in forty milliliters of water. The aluminum sulfate solution was added to the solution of the sulfonamides rapidly with constant stirring. A precipitate of aluminum monosulfamethazine monosulfacetamide monosulfadiazine formed immediately. The precipitate was collected on a fritted glass funnel, washed twice with successive twenty-milliliter portions of water, and finally dried at forty degrees centigrade in a hot air oven. It was completely tasteless. The United States Pharmacopeia assay indicated 85.5 percent of total sulfonamides in the product using the average of the molecular weights of the three sulfonamides present.

Example 4.—Aluminum trisulfisoxazole

In the manner shown in Example 1, aluminum trisulfisoxazole is prepared by reacting sodium sulfisoxazole with hydrous aluminum sulfate in a molar ratio of about three to about one-half. The product proved to be tasteless.

Example 5.—Aluminum trisulfadimetine

In the manner shown in Example 1, aluminum trisulfadimetine is prepared by reacting sodium sulfadimetine with hydrous aluminum sulfate in a molar ratio

of about three to about one-half. The product proved to be tasteless.

Example 6.—Aluminum trisulfathiazole

In the manner shown in Example 1, aluminum trisulfathiazole is prepared by reacting sodium sulfathiazole with hydrous aluminum sulfate in a molar relation of about three to about one-half. The product proved to be tasteless.

Example 7.—Aluminum monosulfadimetine monosulfacetamide monosulfamerazine

In the manner shown in Example 3, aluminum monosulfadimetine monosulfacetamide monosulfamerazine is prepared by reacting aluminum chloride with sodium sulfadimetine, potassium sulfacetamide, and potassium sulfamerazine, the reactants being used in about equimolar quantities. The product proved to be tasteless.

Example 8.—Aluminum monosulfisoxazole disulfaguanidine

In the manner shown in Example 3, aluminum monosulfisoxazole disulfaguanidine is prepared by reacting aluminum chloride with sodium sulfisoxazole and potassium sulfaguanidine in the molar ratio of about one to about one to about two. The product proved to be tasteless.

Example 9.—Aluminum disulfathiazole monosulfanilamide

In the manner shown in Example 3, aluminum disulfathiazole monosulfanilamide is prepared by reacting hydrous aluminum sulfate with potassium sulfathiazole and sodium sulfanilamide in the molar ratio of about one-half to about two to about one. The product proved to be tasteless.

Example 10.—Aluminum disulfamethazine monosulfathiazole

In the manner shown in Example 3, aluminum disulfamethazine monosulfathiazole is prepared by reacting hydrous aluminum sulfate with potassium sulfamethazine and sodium sulfathiazole in the molar ratio of about one-half to about two to about one. The product proved to be tasteless.

Example 11.—Aluminum monosulfadiazine monosulfamerazine monosulfamethazine

In the manner shown in Example 3, aluminum monosulfadiazine monosulfamerazine monosulfamethazine is prepared by reacting aluminum chloride with sodium sulfadiazine, potassium sulfamerazine and sodium sulfamethazine, the reactants being used in about equimolar amounts. The product proved to be tasteless.

Example 12.—Aluminum monosulfadiazine monosulfamerazine monosulfathiazole

In the manner shown in Example 3, aluminum monosulfadiazine monosulfamerazine monosulfathiazole is prepared by reacting aluminum chloride with sodium sulfadiazine, potassium sulfamerazine, and potassium sulfathiazole, the reactants being used in about equimolar amounts. The product proved to be tasteless.

In the manner shown in the above examples, many other aluminum trisulfonamide salts, wherein at least one of the valences of aluminum is satisfied by a member selected from the group consisting of sulfamethazine, sulfacetamide, sulfisoxazole, sulfadimetine, and sulfathiazole, can also be prepared. A representative group of the several types of combinations are as follows:

Aluminum trisulfisoxazole
Aluminum trisulfadimetine
Aluminum trisulfathiazole
Aluminum trisulfamethazine
Aluminum trisulfacetamide
Aluminum disulfisoxazole monosulfadimetine

- Aluminum disulfisoxazole monosulfathiazole
Aluminum disulfisoxazole monosulfamethazine
Aluminum disulfisoxazole monosulfacetamide
Aluminum disulfisoxazole monosulfamerazine
5 Aluminum disulfisoxazole monosulfadiazine
Aluminum disulfadimetine monosulfisoxazole

70 It is to be understood that the invention is not to be limited to the exact details of operation or exact compounds shown and described, as obvious modifications and equivalents will be apparent to one skilled in the art, and the invention is therefore to be limited only by the scope of the appended claims.

I claim:

1. An aluminum trisulfonamide salt having the following formula:

wherein R_1 is a radical selected from the group consisting of sulfacetamide, sulfamethazine, sulfisoxazole, sulfadimetine, and sulfathiazole and R_2 and R_3 are radicals selected from the group consisting of sulfamethazine, sulfacetamide, sulfisoxazole, sulfamerazine, sulfadiazine, sulfapyridine, sulfathiazole, sulfaguanidine, and sulfadimetine.

2. Aluminum trisulfacetamide.

3. Aluminum trisulfamethazine.
4. Aluminum disulfamethazine monosulfathiazole.
5. Aluminum monosulfamethazine monosulfacetamide monosulfadiazine.
6. Aluminum monosulfadiazine monosulfamerazine monosulfamethazine.
7. A process for producing an aluminum trisulfonamide salt which comprises mixing an aqueous aluminum salt solution with an aqueous sulfonamide salt solution containing at least one sulfonamide selected from the group consisting of sulfacetamide, sulfamethazine, sulfisoxazole, sulfadimetine, and sulfathiazole, and separating the thus-produced aluminum trisulfonamide salt.
